BOBBY PIN

Rudolph Erenhouse, Baldwin, N.Y.

Application November 20, 1957, Serial No. 48,568

Term of patent 14 years

(Cl. D86—10)

FIG.2.

FIG.3.

Fig. 2 is a rear elevational view, and
Fig. 3 is a top plan view thereof.

I claim:

The ornamental design for a bobby pin, substantially as shown.
